Primary Examiner — Daniel Bui(74) *Attorney, Agent, or Firm* — Wissing Miller LLP(57) **CLAIM**

The ornamental design for an electrical receptacle tester, as shown and described.

DESCRIPTION

FIG. 1 is a top, first side perspective view of an embodiment of the new design for an electrical receptacle tester in accordance with the present invention;

FIG. 2 is a top, second side perspective view of the electrical receptacle tester shown in FIG. 1;

FIG. 3 is a side elevational view of the first side of the electrical receptacle tester shown in FIG. 1;

FIG. 4 is a bottom perspective view of the electrical receptacle tester shown in FIG. 1;

FIG. 5 is a top view of the electrical receptacle tester shown in FIG. 1; and,

FIG. 6 is another embodiment of a top view of the electrical receptacle tester shown in FIG. 1.

The broken lines within the various embodiments of the claimed design and the spaces therein are for environmental purposes only and form no part of the claimed design.
